UNITED STATES PATENT OFFICE.

HAMILTON C. MOORMAN, OF CHICAGO, ILLINOIS.

DISPENSING DEVICE.

Application filed November 15, 1924. Serial No. 750,204.

To all whom it may concern:

Be it known that I, HAMILTON C. MOORMAN, a citizen of the United States, residing at Chicago, in the county of Cook and State of Illinois, have invented new and useful Improvements in Dispensing Devices, of which the following is a specification.

This invention relates to dispensing devices especially adapted for use in connection with powdered materials, although not necessarily restricted to such use.

Briefly stated, an important object of this invention is to provide a dispensing device having simple means whereby the material is accurately measured preparatory to dispensing the same.

A further object of the invention is to provide a dispensing apparatus of the character specified which is of highly simplified construction, simple to operate, and cheap to manufacture.

Other objects and advantages will be apparent during the course of the following description.

In the accompanying drawing forming a part of this application and in which like numerals are employed to designate like parts throughout the same,

Figure 1 is a side elevation of the improved dispensing device;

Fig. 2 is an end elevation of the same;

Fig. 3 is a plan view of the improved dispensing device;

Fig. 4 is a group perspective of several measuring disks and a supporting ring therefor;

Fig. 5 is a perspective of another disk embodied in the invention and which is employed in connection with the two disks illustrated in Fig. 4.

In the drawing, wherein for the purpose of illustration is shown a preferred embodiment of the invention, the numerals 5 designate a pair of skids or beams which form a support for a cylinder 6. Figs. 1, 2 and 3 illustrate that the cylinder 6 which is of sheet metal or the like has a detachable portion 7 and this detachable portion or section 7 and the major portion of the cylinder are provided with abutting flanges 8 for the reception of fastening devices 9 by means of which the detachable section is held in place. It is believed to be obvious that the section 7 may be easily detached for cleaning the interior of the device or for gaining access

to the inside of the same for the purpose of making repairs or replacements.

Fig. 2 illustrates that a supporting ring 10 is secured in the lower portion of the cylinder 6 by screws or other fastening devices, 60 and is secured upon the upper edges of the supporting members 5 by screws or other suitable fastening devices.

The ring 10 forms a support for a lower disk 12 having a crescent shaped opening 14 65 which forms the final discharge opening for the measured material. The opening 14 is gradually increased in width toward one end and more specifically the opening 14 is increased in width in the direction of rotation 70 of an intermediate disk 15. The disk 15 is of skeleton formation or is somewhat of the formation of a spider. The material which is allowed to drop into the spaces between the spokes 16 of the intermediate disk 15 is 75 swept across the top of the lower disk 12 and into the opening 14. It is thus seen that each time the disk 15 is rotated, a given amount of material will be dispensed from the cylinder. 80

The upper disk 18 is rigidly secured in the lower portion of the cylinder by brackets 19 and is provided with an approximately semi-circular opening 20 for supplying material to the segmental spaces between 85 the spokes 16.

The lower disk 12 is also non-rotatably secured in the lower portion of the cylinder. Suitable fastening devices are employed to secure the disk 12 directly to the ring 10. 90

With reference to the foregoing description it will be seen that the disk 15 turns between the fixed disks 12 and 18 so that each time the disk 15 makes a turn a proper quantity of material will be dispensed into a 95 receptacle 25 or other receiver. The receptacle 25 is positioned between the beams 5 and is held in position thereby.

The intermediate disk 15 has a hub provided with a squared opening 30 for the reception of a drive shaft 31, the upper end of which is rotatably connected to a spider 32. The outer portion of this spider 32 is secured in any suitable manner to the cylinder. 100

The lower portion of the shaft 31 operates 105 in a bearing 34 on the intermediate portion of a cross bar 35, the ends of which are secured to the supporting beams 5. It will be seen that the cross bar 35 not only serves as a support for the shaft 31 but also as a 110

spacing and connecting means for the beams 5.

The shaft 31 is provided with a worm wheel 40 engaged by a worm 41 on a main drive shaft 42 extending from a suitable source of power. By varying the speed of the shaft 42 the quantity of material dispensed may be varied.

In operation, a battery of these dispensing devices may be employed for measuring and dispensing the various ingredients of a stock remedy, food, or the like. All of the dispensing devices may be connected for operation together so as to bring about the proper mixture.

If desired the receptacle 25 may be dispensed with and a traveling belt employed for receiving the measured ingredients as they are dispensed.

The material is originally fed to the cylinder 6 from a hopper 60 having an attaching neck 62 which is detachably received in the upper end of the cylinder. Obviously, the hopper 60 may be of any capacity desired.

Having thus described the invention, what is claimed is:

A dispensing device comprising a cylinder adapted for containing material to be dispensed, an upper disk rigidly secured within the lower portion of the cylinder and having an opening, an intermediate flat disk rotatably mounted beneath said upper disk and having a plurality of openings adapted to successively register with the opening in the upper disk, a lower disk rigidly fixed beneath said intermediate disk and having a substantially crescent shaped discharge opening gradually increased in width in the direction of rotation of the intermediate disk, and with its widest portion disposed radially of the disk to prevent clogging, a drive shaft extending through all of said disks and having driving connection with the intermediate disk, a pair of supporting beams supporting said cylinder, and a ring mounted on said beams and supporting said lower disk.

In testimony whereof I affix my signature.

HAMILTON C. MOORMAN.
